UNITED STATES PATENT OFFICE.

FOLKE F. NORDËN, OF BROOKLYN, NEW YORK, ASSIGNOR OF TWO-THIRDS
TO ANDREW J. MURPHY, OF NEW YORK, N. Y.

PROPELLED MECHANISM.

SPECIFICATION forming part of Letters Patent No. 776,416, dated November 29, 1904.

Application filed November 30, 1903. Serial No. 183,250. (No model.)

To all whom it may concern:

Be it known that I, FOLKE F. NORDËN, a citizen of the United States, residing at Brooklyn, in the county of Kings and State of New York, have invented certain new and useful Improvements in Propelling Mechanisms; and I do hereby declare the following to be a full, clear, and exact description of the invention, such as will enable others skilled in the art to 10 which it appertains to make and use the same.

This invention relates to improvements in propelling mechanisms for aerial and also marine vessels.

The object of the invention consists in the 15 construction of means mounted entirely within the framework of a ship or the like, whereby motion is imparted to the same.

Another object of the invention is to provide a suitable compartment within a vessel, 20 said compartment communicating with the sides thereof and a plurality of secondary compartments or casings communicating with said primary compartment and diverging therefrom to the sides of said vessel.

Another object of the invention is to provide means in said compartments whereby one or all may be entirely closed, and thereby providing a water or air tight casing or compartment.

Another object of the invention is to provide propelling means mounted within said compartments and simultaneously actuated for imparting motion to a vessel carrying the said propelling means.

With these and further objects in view the invention consists in certain other novel constructions, combinations, and arrangements of parts, as will be hereinafter fully described and claimed.

In the accompanying drawings, Figure 1 represents a longitudinal fragmentary sectional view of the hull of a ship and the propelling mechanism therefor. Fig. 2 represents a fragmentary perspective view of the 45 hull of a ship and the casings retained therein, in which are mounted propelling means for said ship. Fig. 3 represents a fragmentary plan view of one of the propelling-shafts and a valve and its operating mechanism mounted

thereon. Fig. 4 represents a vertical fragmentary sectional view of a device similar to that shown in Fig. 3. Fig. 5 represents a side elevation of the worm-gear and clutch mechanism therefor for controlling the actuation of the rotary valves. Fig. 6 represents an end view of a valve-casing and a sliding valve mounted therein. Fig. 7 represents a fragmentary plan view of one of the secondary casings, showing a slide-valve mounted thereon, partly in section. Fig. 8 represents another embodiment of my invention shown in longitudinal fragmentary sectional view of the same.

Referring to the drawings by numerals, 1 designates the hull of a vessel, and 2 represents a primary compartment or casing removably mounted therein and extending transverse of the same. Said compartment is connected with ports 3, formed in the side of the vessel, said ports being provided with screens 4, which entirely cover the same.

As shown in Fig. 2, I provide suitable guides 5 upon the sides of the vessel, and within the guides are mounted vertically-sliding valves 6, which may be actuated by any suitable means, connected at 7, for closing and opening the same.

In Fig. 1 of the drawings I indicate a sliding valve 8, which is adapted to extend transversely of the compartments near the ports 80 and to be operated manually when desired. A plurality of secondary casings 9 are assembled in communication with said primary casing 2 and opening outside of the hull of the vessel. These casings or compartments 9 are 85 greater in diameter at the point of communication with the primary compartment 2 than at the outer end connected with the side of the vessel. I preferably arrange the secondary casings 9 in positions extending at different angles from the main casing 2. Near the outer end of the secondary casings 9 are arranged valves 10 for closing the outer ends thereof when desired. The construction of these valves 10 will be hereinafter fully described. Within the casings 9 are mounted screw-propellers 11, said screw-propellers being retained within said casing by means of

bars 12. (Shown in Figs. 6 and 7.) Said bars 12 provide means upon which the shafts 13 are journaled, said shafts 13 extending through the casings 9 and the compartment 2 into the main portion of the vessel and are provided at their inner ends with suitable beveled gear-wheels 14. The shaft 13 is mounted at its inner end upon a suitable standard 15. The beveled gear-wheel 14 is loosely mounted upon the shaft 13 and is always connected with the adjacent gear-wheels, and said wheels are provided with a beveled wheel 16, which is connected with the motor or any other suitable driving mechanism and which imparts motion to the said beveled gear-wheels 14. Upon the upper portion of the standard 15 is mounted a lubricating device 17. If it is desired to rotate a particular shaft, it will be necessary to slide the annular clutch-sleeve 18 upon the shaft 13 by means of the lever-arm 19, and the said member 18 is adapted to engage the beveled gear-wheel 14, and thereby actuate the shaft 13. By this construction I can simultaneously operate all the shafts carrying the propellers, or if it is desired to have only one shaft and propeller in operation by throwing the clutch mechanism this result can be obtained. It is obvious that one or all can be thrown out of operation by the described clutch mechanism.

In this invention I do not claim any special motive power, as it will be apparent that the propellers can be actuated by a steam-engine or an electric motor.

35 The sliding valves 10 are mounted upon the tubular casings 9 near their discharge ends and are constructed by assembling upon the casings 9 a box or casing 20, which is constructed of a plurality of parts and is retained
40 in a fixed position by any suitable means. Within this casing 20 is slidably mounted a valve member 21, which is provided with means for manually sliding the same. Upon the casing or compartment 2 is formed a
45 recessed portion 22. Upon the shafts 13 are mounted rotary valves 23. These valves 23 are constructed by assembling therewith a tubular shaft 24, which is screw-threaded upon its periphery, and upon one of the faces of the valve
50 23 is mounted a packing 25, which is secured in its normal position by means of a sleeve or plate 26, said plate being retained in an assembled position upon the valve member 23 by means of bolts 27 or like means. In the
55 drawings I have shown said members 23 provided with an annular hollow projection 28. Within said projection 28 is suitable packing which is adapted to engage the shaft 13. Upon the casing of the compartment 2 is formed an
60 annular hollow casing 29, within which is mounted suitable packing. Upon the casing forming compartment 2 is an arm 30, extending therefrom, which is provided with means whereby the actuation of the hollow cylindrical sleeve 24 is controlled. If it is desired
65

to close one of the openings 31 formed upon the secondary casings 9, it will be necessary to rotate the wheel 32, which imparts motion to the longitudinal shaft 33, carrying a plurality of worm-wheels 34. These wheels 34 are adapted to engage gear-wheels 35, mounted upon the valve-shaft 24. The said gear-wheel 35 is slidably mounted upon shaft 24 and is provided with an extension which engages a longitudinal groove formed upon said shaft. If it is desired to actuate only one of the rotary valves, it will be necessary to throw the others out of engagement with the operating mechanism, and this result is obtained by pivoting the lever 36 upon its fulcrum, and thereby moving the worm - wheel 34 longitudinally upon the shaft 33 until the said wheel 34 is out of engagement with the gears formed upon wheel 35. It will be obvious that by this mechanism for controlling the valves mounted upon the shafts 13 one or all can be operated, and if it is desired the ends 31 of the tubular casings 9 may be closed.

Each of the compartments is provided with waste-pipes 52, whereby the said compartments may be drained when all the valves are in a closed position, thereby forming an air or water tight compartment. 90

By the projections 22^a, formed upon the casing or compartment 2, a recessed portion 95 22 is formed upon said casing and in which the valves 23 are normally retained. By retaining said valves 23 within this recessed portion of the casing they will be entirely removed from the path of supply as the water 100 or the like is supplied to the propellers 11.

The casings 9 are provided with removable covers 37, being retained in a fixed position upon said casings by any suitable fastening means. Upon the primary casing or compartment 2 is also mounted a hinged or removable cover 38. By the construction of the casings and the arrangement of the valves it will be apparent that any one or all of the same may be closed, and by removing the covers access to the interior thereof will be obtained. In the event of a propeller becoming disabled it will not be necessary to stop the progress of the ship, but only the operation of the particular propeller, and by closing the valves, as heretofore described, examination of the particular compartment can easily be made. 105 110 115

A lubricating device 39 is mounted upon the extension 30, which is formed integral with the casing 2. 120

In Fig. 8 the propeller-shafts 13 are arranged in parallel position, and instead of employing the bevel-gears 14, as is shown in Fig. 1, I employ gear-wheels 14^a for the purpose of imparting motion to the propellers. 125 The compartments or casings, as shown in Fig. 8, are arranged in parallel position and are so constructed as to discharge the water which is passed through the same into a common compartment 50, which is provided with 130

an opening 51 at the stern of the vessel. The propeller-blades, as shown in Fig. 8, are not provided with a central shaft or reinforcing portion extending the length of the same, as shown in Fig. 1; but the said propellers are provided with a screw-blade, which is secured to the shafts 13, at one end thereof. The detail construction of the compartments in this modification is practically the same as that heretofore described for the construction of the device shown in the other figures of the drawings.

It will be seen that upon the closing of the valves 10 at the ends of each of the parallel casings containing the propellers the said compartment formed by the closure of said valve 10 will prevent any water from passing through the closed compartment. It will be apparent upon considering the specification and drawings that the valve 8 can be so arranged as to control the inflow of the water into the compartments containing the propellers.

In the construction described it will be apparent that I have provided means for actuating all of the shafts carrying the propellers simultaneously; but, if it is desired, any one of said shafts may be thrown out of operation by the clutch mechanism. If it is necessary to examine any or all of the compartments containing the propelling means, I have provided means whereby accomplishment of the same can easily be obtained.

In the construction of the device if it is desired to provide a casing 41 extending the entire length of a ship this can be accomplished by connecting the said casing with a port near the bow of a vessel and extending the same under the propelling means to the primary casing 2. I have shown in Fig. 1 in dotted lines this proposed embodiment of the invention and have also disclosed a valve 10^a (shown in dotted lines) therefor.

Having thus fully described my invention, what I claim as new, and desire to secure by Letters Patent, is—

1. In a device of the character described, the combination with a vessel, of a communicating primary and an auxiliary compartment, propelling means mounted within the auxiliary compartment, and means slidably mounted entirely within the primary compartment for preventing communication with said auxiliary compartment.

2. In a device of the character described, the combination with a ship, of a primary casing mounted therein and extending transversely thereof, a plurality of secondary casings communicating with said primary casing, and each of said casings provided with a hinged cover.

3. In a device of the character described, the combination with a ship, of a primary casing extending in a transverse position and mount-

ed therein, secondary casings communicating with said primary casing, rotary propelling means mounted within said secondary casings, and means for separately closing said casings.

4. In a device of the character described, the combination with a ship, of a primary casing extending across the same and provided with a plurality of secondary casings, removable covers for said casings, propellers mounted within said secondary casings, and a plurality of valves assembled with said casings for closing the same.

5. In a device of the character described, the combination with a ship, of a primary compartment formed therein, a plurality of secondary casings communicating with said primary casing, propellers mounted within said secondary casings, rotary valves mounted within said primary casing, and means for actuating said valves.

6. In a device of the character described, the combination of a primary casing, a secondary casing extending therefrom, a propeller mounted within said secondary casing and connected with means for actuating the same, rotary and sliding valves assembled with said casings for closing the openings formed therein.

7. In a device of the character described, the combination of a casing having a plurality of openings, said casing provided with a hinged lid, and means assembled with said casing for closing the openings formed therein.

8. In a device of the character described, the combination with a compartment provided with a propeller, and means assembled therewith for actuating said propeller, of rotary, sliding valves assembled with said casing and adapted to entirely incase said propeller within said casing.

9. In a device of the character described, the combination with a casing, of a shaft provided with a propeller rotatably mounted within said casing, a rotary valve mounted upon said shaft and provided with means for sliding the same upon said shaft.

10. In a device of the character described, the combination with a casing, of a shaft mounted therein, said shaft provided with a propeller and a valve, said valve mounted upon said shaft and provided with means for adjusting the position thereof upon said shaft.

11. In a device of the character described, the combination with a compartment, of a plurality of casings communicating therewith, shafts mounted in said casing and provided with propellers, a valve mounted upon each of said shafts, and means assembled with said valves for simultaneously actuating the same.

12. In a device of the character described, the combination of a casing, shafts mounted in said casing, propellers carried by said shafts, a plurality of valves mounted upon

said shafts, and said valves provided with hollow sleeves connected with means for adjusting the same.

13. In a device of the character described, 5 the combination with a compartment, of a shaft mounted therein, a propeller mounted upon said shaft, a valve provided with a sleeve mounted upon said shaft, and means connected with said sleeve for rotating the same 10 and thereby imparting motion to said valve.

14. In combination with a vessel, of a plurality of cylindrical casings mounted therein, propellers mounted within said casings, and means assembled with said propellers for 15 simultaneously actuating the same.

15. In a device of the character described, the combination with a casing, of propellers mounted therein, valves assembled with said propellers, means connected with said valves 20 for simultaneously imparting motion thereto.

16. In a device of the character described, the combination with a primary casing, of a plurality of secondary casings extending therefrom, propelling means carried within said 25 secondary casings, removable covers mounted upon said casings, a plurality of slide-valves assembled upon the outer ends of said casings, a plurality of rotary valves secured within said primary casing, and means for actuating said 30 rotary valves and thereby moving the same longitudinally within said primary casing.

17. In a device of the character described, the combination with a casing, of a propeller mounted therein, a slide-valve mounted upon 35 said casing, a valve assembled with said propeller and provided with means for longitudinal adjustment, and a clutch mechanism assembled with said propeller for controlling operation thereof.

18. In a device of the character described, the combination with a primary casing, of a plurality of secondary casings extending at an 40 angle therefrom, a plurality of rotating shafts mounted within said casings and propellers secured thereto, a plurality of slide-valves rotatably mounted upon said shafts, said valves provided with a hollow sleeve formed integral therewith and extending at right angles thereto, gear-wheels mounted upon said sleeve, and 45 means engaging said gear-wheels for imparting motion thereto.

19. In a device of the character described, the combination with a casing, of a plurality of secondary, converging casings secured 50 thereto, shafts mounted within said casings and provided with propellers mounted thereon, said shafts extending through said primary casing and provided with means for imparting motion thereto, a plurality of longitudinal, adjustable valves mounted upon said 55 shafts, and means assembled with said valves for adjusting the same longitudinally upon the shafts.

20. In a device of the character described, 60 the combination of a primary, recessed cas-

ing, secondary casings extending therefrom, hinged covers mounted upon said casings, slide-valves mounted upon said casings and adapted to close their outer ends, a plurality of valves mounted within said primary casing and adapted to be normally retained within said recessed portion thereof, and means for adjusting said valves in a horizontal plane. 70

21. In a device of the character described, 75 the combination of a primary casing provided with a plurality of openings, part of said openings being provided with screens, slide-valves mounted upon said casing near said openings provided with said screens, rotary sliding means carried within said primary casing for 80 closing openings formed therein, and rotary means assembled with said casing for imparting motion to a vessel.

22. In a device of the character described, 85 the combination of a compartment provided with openings extending transverse of a vessel, sliding and rotary means assembled with said compartment for closing said openings formed therein, a plurality of secondary compartments extending therefrom, a plurality of 90 shafts mounted with said compartments, said shafts provided with propellers, and means connected with said shafts for imparting motion thereto.

23. In a device of the character described, 95 the combination of a primary compartment extending transversely of a ship, a plurality of casings connected with said compartment and provided with propelling means, means assembled with said compartments for entirely closing the same, and means removably mounted upon said compartments permitting of access to the same. 100

24. In a device of the character described, 105 the combination of a compartment extending transverse of a vessel, a plurality of compartments secured to said primary compartment and extending at an angle thereto, said secondary compartments converging at their discharge end, propelling means mounted 110 within said compartments secured to the primary compartment, and means carried by the compartments for forming separate closed compartments. 110

25. In a device of the character described, 115 the combination with a vessel, of a compartment formed therein and extending transversely thereof, secondary compartments communicating with said primary compartment, said secondary compartments converging toward their outer ends, said compartments being formed with openings, and means assembled with said compartments for closing said openings, and thereby producing separate closed compartments. 120

26. A propelling mechanism, comprising a recessed compartment formed with end portions extending at an angle to said compartment, an auxiliary or secondary communicating compartment assembled with said re- 125

cessed compartment, propelling means mounted within said auxiliary compartment, and means normally inclosed within said recessed compartment for closing one end of said auxiliary compartment.

27. A propelling mechanism, comprising a compartment, secondary communicating compartments assembled therewith, a plurality of parallel horizontal propellers assembled within said compartments, and means for imparting motion to said propellers.

28. In combination with a propeller, a casing provided with a removable cover inclosing said propeller, said casing provided with openings, a motor assembled with said propeller, and means mounted upon said propeller and adapted to move independently thereon for closing one of said openings formed upon the casing.

29. In a device of the character described, the combination with a vessel, of a primary compartment mounted therein, secondary communicating compartments secured to said primary compartment, propellers mounted within said secondary compartments, sliding-valve means mounted upon the propeller-shafts, and means extending transversely of the propeller-shafts for operating said sliding-valve means.

30. A propelling mechanism, comprising a primary compartment provided with openings extending therefrom at an angle thereto, a plurality of secondary communicating compartments secured to said primary compartment, means mounted near the end of each compartment for closing the same, propelling means assembled with each secondary compartment, and separate means carried within said primary compartment for closing the inner end of each of said secondary compartments.

31. In a device of the character described, the combination with a vessel, of communicating compartments formed therein, said compartments provided with openings, propelling means mounted within one of said compartments, rotary sliding-valve means mounted within the other compartment for preventing communication, and sliding-valve means for closing the other openings in both compartments.

32. In a device of the character described, the combination with a primary compartment, communicating, secondary compartments assembled therewith, propelling means in said secondary compartments, and means carried within said primary compartment for closing the inner ends of said secondary compartments.

33. A propelling mechanism, comprising a horizontal propeller, a cylindrical casing inclosing the same, a motor assembled with said propeller, a longitudinal, manually-reciprocating means assembled with said propeller, and connecting means between said propeller and motor, whereby motion is imparted to said propeller.

34. A propelling mechanism, comprising a plurality of propellers, inclosing means for said propellers, said closing means provided with inlet and outlet openings, manually-reciprocating valve means for closing said inlet-openings, and means for imparting motion to said propellers.

35. A propelling mechanism, comprising propelling means, a casing inclosing said propelling means, said casing provided with an inlet and outlet opening, transverse sliding means for closing said outlet-opening, rotary means for closing said inlet-opening, a motor assembled with said propelling means, and means connecting said motor with said propelling means.

36. A device of the character described, comprising a primary casing, a plurality of auxiliary communicating casings assembled therewith, each casing provided with discharge means intermediate its length, propelling means assembled within said auxiliary casings, and valve means assembled with said casings for closing each of their ends.

37. In a device of the character described, the combination with a vessel, of a primary casing mounted therein, comprising a compartment extending throughout the entire length of said vessel, communicating compartments extending from said primary compartment upon each side thereof and intermediate its ends, and propelling means assembled with said compartments.

38. In a device of the character described, the combination with a vessel, of a transverse compartment mounted within said vessel, a longitudinal compartment communicating with said transverse compartment and extending the entire length of said vessel, propelling means mounted within said compartments, sliding-valve means assembled with said compartments near their outer ends, and rotary-valve means mounted within said transverse compartment.

In testimony whereof I hereunto affix my signature in presence of two witnesses.
